COLD STORAGE LOCKER ROOM

Roy W. Smith, Newark, Ohio

Application July 28, 1938, Serial No. 221,769

5 Claims. (Cl. 62—89)

My invention relates to a cold storage locker room. It has to do, more particularly, with the arrangement of lockers in a cold storage room, the lockers being adapted to receive perishable food products or other perishable products.

Recently the use of individual lockers in cold storage plants has become quite popular. Most of the cold storage companies at the present time have cold storage rooms in which a plurality of individual lockers are arranged. These lockers are rented to the general public. For example, they may be rented to merchants, farmers or large families so that the person renting the locker can buy large quantities of food at a lower price and store this food in his locker, withdrawing small amounts from the locker as needed. Heretofore, it has been necessary for an individual when he desires to remove something from his locker or place something therein to go into the cold storage room where the lockers are disposed. The temperature in these cold storage rooms is usually about zero and, obviously, this extremely low temperature is very uncomfortable to the individual and might be harmful to him.

In the past, the lockers have been arranged in rows in the cold storage room with aisles therebetween. Thus, it is not only necessary to refrigerate the space actually occupied by the cold storage lockers but it is also necessary to refrigerate the aisles and other spaces around the lockers which are provided so that access can be had to the lockers. Of course, the net operating cost of the cold storage room increases in accordance with the increase in space required to be refrigerated in proportion to the space actually occupied by the lockers and which is rented to the individuals. Obviously, it would be desirable to refrigerate only the space actually occupied by the lockers.

One of the objects of my invention is to provide a cold storage locker room arrangement of such a nature that access may be had to individual lockers without going into the refrigerated space actually occupied by the lockers.

Another object of my invention is to provide a cold storage locker room arrangement which is of such a nature that it is necessary to refrigerate substantially only the actual space occupied by the lockers but easy access may still be had to the lockers.

In its preferred form my invention contemplates the provision of a building structure having a novel arrangement whereby the above-indicated objects are accomplished. This build-

ing structure is preferably provided with a large room which is divided into a lower locker chamber and a separate upper room or chamber. The lower locker chamber is adapted to be fully insulated and has means disposed therein for refrigerating such chamber to bring it to a very low temperature, for example, zero. The upper room or chamber is not adapted to be refrigerated to a low degree but is preferably at ordinary room temperature and may be air-conditioned if desired. A horizontally disposed wall divides the upper chamber or room from the lower locker chamber and is made up mainly of a plurality of doors or lids which may be opened individually in order to permit raising of individual lockers from the lower chamber upwardly into the upper chamber or room. The lockers are disposed in suitable guides and may be moved vertically by means of a suitable hoist disposed in the upper room.

Thus, it will be apparent that a person desiring to gain access to his individual locker, need only go into the upper room which is at ordinary room temperature or a moderate temperature and his locker may be raised easily and quickly into the upper room where he may remove articles therefrom or place articles therein. After he is finished with his locker, it may be quickly and easily lowered into the refrigerated locker chamber and the cooperating door or lid may be closed over the locker in order to close and seal the locker chamber.

Various other objects and advantages will be apparent from the following description.

The preferred embodiment of my invention is illustrated in the accompanying drawings wherein similar characters of reference designate corresponding parts and wherein:

Figure 1 is a perspective view of a portion of a building structure showing the preferred arrangement of the lockers.

Figure 2 is a horizontal section through a building which may be provided with my locker room arrangement.

Figure 3 is a vertical section through a portion of the locker chamber taken substantially along line 3—3 of Figure 2.

Figure 4 is a detail mainly in section showing the upper end of a locker and showing the space through which it may be raised and the lid or door for closing and sealing said space.

Figure 5 is a more or less diagrammatic view showing a hoist which may be used in raising the lockers and showing means for controlling such hoist.

With reference to the drawings I have illustrated in Figure 2 a building structure 1 in which my cold storage locker room arrangement may be incorporated. The building may include 5 a room 2 which may be used as a cutting room for cutting meats to be placed in the lockers or may be used for other purposes. It also includes a room 3 which may be used as a chill room in which the food products to be placed in the lockers may be first chilled slightly. The building is further provided with a large room 3a which may be arranged according to my invention.

As indicated in Figure 1 the large room 3a is 15 divided into a lower locker chamber 4 and an upper room or chamber 5. The room 4 is adapted to contain a plurality of ventilated lockers 6 and is adapted to be refrigerated to a low temperature while the upper room or chamber 5 is 20 adapted to be substantially empty until the lockers are raised thereinto, in a manner to be explained hereinafter.

The locker chamber 4 has all of its walls fully 25 insulated. Each wall embodies an inner slab 7 and an outer slab 8 of concrete or other suitable material having the space therebetween filled with cork 9 or other suitable heat-insulating material. A large number of the lockers 6 are disposed in this chamber. Each of the lockers 6 30 extends from the bottom of the chamber 4 substantially to the top thereof. Furthermore, each locker may embody a plurality of horizontally spaced locker spaces, access to which may be gained by means of doors 10. The lockers are 35 arranged in the chamber 4 in rows which are slightly spaced from each other. The spaces between the rows of lockers have pipes 11 extending therethrough which are adapted to carry a suitable refrigerant. These pipes 11 are supported by vertically disposed bars 12 which have their lower ends attached to wooden planks 13 mounted on the floor of the chamber 4.

The upper ends of the bars or supports 12 carry longitudinally extending wood beams 14. Obviously, the bars 12 are disposed at spaced 45 intervals in a row and each row supports a beam 14. The beams 14 are continuous from one wall of the building to the other. A plurality of transversely disposed short beams 15 are 50 provided at longitudinally spaced intervals along the beams 14. Thus, it will be apparent that the beams 14 and the beams 15 cooperate to form a plurality of substantially square spaces 16 through which the lockers may be raised into 55 the chamber 5. These beams also serve to support a horizontally disposed floor or wall which will divide the upper chamber 5 from the lower chamber 4. A lid or door 17 is provided for closing and sealing each of the spaces 16. This 60 lid or door may be made of wood and preferably has layers 18 and 19 of insulating material on the upper and lower surfaces thereof. I preferably arrange the doors 17 in pairs, the two adjacent lids being hinged together as indicated at 20. These lids or doors rest on rubber strips 21 secured to the top edges of the beams 14 and 15 in order to obtain a tight seal.

The lockers 6 are preferably made of heavy 70 gauge steel. It will be noted from Figure 4 that each beam 14 is provided with weather strips 22 which are secured thereto and the free edges of which bear against the side surfaces of the lockers 6. Similar strips are provided on the beams 15. Thus, these weather strips will serve 75 to seal the spaces between the side walls of the

locker 6 and the surfaces of the beams 14 and 15 regardless of the vertical position of the lockers. When the lockers are in their lowermost position, as indicated in Figure 3, they will rest on the upper surfaces of the wood beams 13 which are secured to the bottom of chamber 4. At this time, the lid 17 will be in position closing the space 16 and the weather strips 22 will also aid in sealing this space. When the locker is raised up into the chamber 5, the space will still be sealed by the weather strips 22. Thus, substantially all the cold air will be retained in the chamber 4. Furthermore, since the chamber 4 is disposed below the chamber 5, there will be no danger of any appreciable amount of cold air 10 escaping upwardly because the cold air will tend to settle downwardly.

If desired, a narrow compartment 23 may be provided at one side of the chamber 4 which may be a quick-freezing compartment. This compartment 23 may be divided from the rest of the chamber 4 by an insulated wall member 24. The temperature in the chamber 23 is adapted to be lower than the temperature in the chamber 4. For this purpose a greater length of refrigerator 25 pipe 11 per cubic foot of space in the chamber 23 may be provided than in the chamber 4. For example, in the compartment 23 the temperature may be 15 or 20 degrees below zero while in the chamber 4 it may be zero. Instead of having 30 ventilated lockers in the compartment 23, I preferably provide steel racks 25 which may support removable wire meshed baskets 26. These racks 25 may be disposed in the same manner that the lockers 6 are disposed for vertical adjustment upwardly through the spaces 16. It will be apparent that the longitudinally extending beams 14 and the transversely extending beams 15 will serve as guides for the lockers and racks during raising and lowering thereof.

It will be apparent that the lids 17 will serve to form the floor of the chamber 5. These lids are all disposed substantially contiguous with each other. When it is desired to raise a locker into the chamber 5, the lid above said locker 45 may be swung to one side exposing the upper end of the locker. Each locker and rack is provided with a pair of hooks 27 on its upper end which may be engaged by hoisting mechanism so that the locker or rack may be raised.

In Figure 1, I show hoisting mechanism of a type which I preferably employ. This mechanism may take the form of a transversely extending I-beam 28 which has rollers 29 on its opposite ends which operate on longitudinally 55 extending beams 30 secured to the side walls of the chamber 5 adjacent the ceiling thereof. The beam 28 carries a hoist 31 which is mounted on rollers 32 for movement therealong. The hoist 31 may be an electric hoist of a suitable type 60 embodying a drum 33 driven by means of an electric motor 34. The drum 33 is rotatably mounted by being keyed to a shaft 35 which is rotatably disposed in bearings secured in supports 36 which carry the rollers 32 at their upper 65 ends. A cable 37 has its upper end attached to the drum 33. Its lower end is secured to a chain 38 which has its ends fastened to a lifting bar 39 that is adapted to be passed beneath the pair of hooks 27 on the locker.

The shaft 35 upon which the drum 33 is mounted is extended and is threaded as indicated at 49. This threaded portion of the shaft passes through a threaded opening in the lower portion of the member 41. The upper end of the member 41 has 75

5 an angular opening through which an angular rod 42 passes. This member 41 is free to move longitudinally on the rod 42 but will not rotate thereon. The rod 42 is rigidly secured to one of the supports 36. The lower portion of the member 41 is provided with a cam portion 43 adapted to actuate mercury contact switches 44 and 45 disposed at opposite sides thereof. These switches are connected in series with the reversible electric 10 motor 34, with a magnetic switch 44a, and with manually operable master or starting switches 46. By actuating one of the switches 46, the motor 34 will be started and the drum 33 will be rotated. The drum 33 is rotated in the proper 15 direction to raise the locker and the member 41 will be moved by threaded portion 48 to the right until it contacts the switch 45. At this time the current to the motor will be shut off inasmuch as the locker 6 will be at the proper level so that 20 access may be had thereto. However, the lower end of the locker will still be within the guides formed by members 14 and 15. To lower the locker, the other switch 46 is actuated completing the circuit to the motor and reversing rotation 25 of the drum 33. This will cause the member 41 to be moved to the left until it strikes the switch 44 which will break the circuit to the motor. At this time, the locker 6 will be at its lowermost 30 position resting on the bottom of the chamber 4. Thus, the hoist will be automatically stopped when the locker has been raised to the proper extent and again when it has been returned to its lowermost position.

35 It will be apparent from the above description that I have provided a cold storage locker room arrangement having many advantages. When a person desires to gain access to his individual locker, he merely walks into the chamber or room 5 which will be at ordinary room temperature and which may be air-conditioned for comfort. 40 The person entering the room or chamber 5 will walk on the floor formed by the lids 11. The lids may be numbered or provided with other indicia and the lid over his particular locker may be 45 swung open. Then the hoist may be moved to a position over the locker, attached to the locker, and the locker may be raised, as indicated in Figure 1. As previously stated, even when the locker is in its uppermost position the space between it and the members 14 and 15 is sealed. 50 Thus, a person placing things in his locker or removing them therefrom need not be subjected to the uncomfortable and harmful extreme cold in the chamber 4. As soon as the person is finished with his locker, it may be lowered into the 55 chamber 4 and the lid 11 replaced. It will be apparent that comparatively small spaces are provided between the various lockers. Thus, a minimum amount of space need be refrigerated.

60 In practice, if food is to be placed in the locker 6, it is first placed in baskets 28 which are then placed on the racks 25, the racks being then lowered into the quick-freezing chamber 23. After they are frozen therein, they are removed and 65 placed in the lockers 6.

65 In the following claims where I refer to lockers it is to be understood that I also intend to cover racks.

70 Various other objects and advantages will be apparent from the preceding description, the drawings and the following claims.

Having thus described my invention, what I claim is:

1. In a building structure, a room, said room 75 being divided by a horizontally disposed partition

into a lower locker chamber and an upper room or chamber into which individual lockers may be raised for access thereto, said lower chamber being insulated, refrigerating means disposed in said lower chamber for bringing it to a low temperature, a plurality of lockers normally disposed in said lower chamber, said partition being provided with a space above each locker through which the locker may pass, a plurality of lids for closing said spaces and for forming the floor of 10 said upper chamber, means for raising and lowering individual lockers through said spaces, and means for sealing each of said spaces regardless of the position of the locker cooperating therewith. 15

2. In a building structure, a room, said room being divided by a horizontally disposed partition into a lower locker chamber and an upper room or chamber into which individual lockers may be raised for access thereto, said lower 20 chamber being insulated, refrigerating means for bringing said lower chamber to a low temperature, said horizontally disposed partition serving to insulate said upper chamber and said lower chamber from each other, a plurality of lockers 25 normally disposed in said lower chamber, said partition being provided with a space above each locker through which the locker may pass, the cross-sectional area of said space and said locker being substantially the same, a plurality of members other than the lockers for closing said spaces 30 and for forming the floor of said upper chamber, and means for raising and lowering individual lockers through said spaces.

3. In a building structure, a room, said room 35 being divided by a horizontally disposed partition into a lower locker chamber and an upper room or chamber into which individual lockers may be raised for access thereto, said lower chamber being insulated, refrigerating means for 40 bringing said lower chamber to a low temperature, said horizontally disposed partition serving to insulate said upper chamber and said lower chamber from each other, a plurality of lockers 45 normally disposed in said lower chamber, said partition being formed by a plurality of longitudinally extending beams and transversely extending beams forming rectangular openings corresponding substantially in shape and area to the cross sectional shape and area of said 50 lockers, the lockers being adapted to pass through said openings, a plurality of lids resting on said beams for closing said spaces and for forming the floor of said upper chamber, and means for raising and lowering individual lockers through 55 said spaces.

4. In a building structure, a room, said room being divided by a horizontally disposed partition into a lower locker chamber and an upper room or chamber into which individual lockers 60 may be raised for access thereto, said lower chamber being insulated, refrigerating means disposed in said lower chamber for bringing it to a low temperature, said horizontally disposed partition serving to insulate said upper chamber and said 65 lower chamber from each other, a plurality of lockers normally disposed in said lower chamber, said partition being provided with a space above each locker through which the locker may pass, the cross-sectional area of said space and said 70 locker being substantially the same, a plurality of lids for closing said spaces and for forming the floor of said upper chamber, a hoist disposed in said upper chamber for raising and lowering individual lockers through said spaces, and means 75

for limiting the uppermost position of the individual lockers so that when each locker reaches its uppermost position it will still extend into the space with which it is associated.

5. In a building structure, a room, said room being divided by a horizontally disposed partition into a lower locker chamber and an upper room or chamber into which individual lockers may be raised for access thereto, said lower chamber being insulated, refrigerating means disposed in said lower chamber for bringing it to a low temperature, said horizontally disposed partition serving to insulate said upper chamber and said lower chamber from each other, a plurality of lockers normally disposed in said lower chamber,

said partition being provided with a space above each locker through which the locker may pass, the cross-sectional area of said space and said locker being substantially the same, a plurality of lids for closing said spaces and for forming the floor of said upper chamber, a hoist disposed in said upper chamber for raising any of said lockers, said hoist being mounted for movement both laterally and longitudinally of said upper chamber so that it may be positioned over any of said lockers, and means for controlling said hoist, said means including means for rendering said hoist inoperative when the locker reaches its uppermost position or its lowermost position.

ROY W. SMITH.
